UNITED STATES PATENT OFFICE.

JOHN FLECK, OF TARENTUM, PENNSYLVANIA.

HEADLIGHT FOR STREET-CARS.

1,089,200.

Specification of Letters Patent. Patented Mar. 3, 1914.

Application filed April 25, 1913. Serial No. 763,627.

To all whom it may concern:

Be it known that I, JOHN FLECK, a citizen of the United States, residing at Tarentum, in the county of Allegheny and State of Pennsylvania, have invented new and useful Improvements in Headlights for Street-Cars, of which the following is a specification.

This invention relates to headlight controls for street cars, the object in view being to provide a headlight mounted for pivotal movement on a vertical axis, combined with means under the control of the motorman or driver for swinging said lamp to one side or the other, in order to illuminate the desired portion of the roadway in front of the car.

One of the principal aims of the present invention is to provide a novel form of control box for the pedal operated plungers, by which the headlight is turned, whereby a combined closure or guard is provided for said plungers, and at the same time a heel rest for the operator which greatly facilitates the operation of said plungers.

With the above and other objects in view, the invention consists in the construction, combination and arrangement of parts, as will be hereinafter more fully described, illustrated in the accompanying drawings, and pointed out in the claim hereunto appended.

In the drawings: Figure 1 is a vertical longitudinal section through one end of a car, showing the lamp controlling mechanism applied thereto. Fig. 2 is a detail vertical section through the control box, showing the same closed in full lines and open in dotted lines. Fig. 3 is a vertical cross section taken adjacent to the plungers and cross head. Fig. 4 is a perspective view of the control box open.

Referring to the drawings, 1 designates the forward portion of the platform of an ordinary street railway car, and 2 the dash extending upwardly from the platform. In front of the dash is arranged a headlight or lamp 3 which is mounted to turn on a vertical axis, the lamp 3 being for that purpose provided with a downwardly extending sleeve 4 at the bottom thereof, forming a socket which receives the upper reduced extremity 5 of a vertical rock shaft 6. The lamp 3 is secured fixedly to the shaft 6 by means of a binding screw 7. The shaft 6 is journaled in a bearing 7' fastened to the front of the car by bracket arms 8, as shown,

and at a suitable point the shaft 6 is provided with a ball race 9 fast thereon and containing a circular series of anti-friction balls 10 which move in a cup or race 11 at 60 the upper extremity of the bearing 7, thus enabling the lamp 3 to be turned easily.

On its lower end, the shaft 6 is provided with a bevel gear wheel 12 which meshes with and is driven by a corresponding bevel gear wheel 13 on the forward end of a rock shaft 14, the last-named shaft being mounted in suitable bearing hangers 15 secured to the bottom of the platform 1. In order to prevent longitudinal movement of the shaft 14, 70 the latter is provided with collars 16 adjustable by means of set screws 17 and bearing against the opposite extremities of the hangers 15, as clearly shown in Fig. 1.

At its rear end, the shaft 14 is provided 75 with a cross head or two-armed lever 18 having the opposite extremities thereof slotted, as shown at 17, to receive pins 20 at the lower extremities of a pair of plungers 21, the lower ends of which are slotted to embrace the opposite ends of the cross head or lever 18. These plungers 21 work up and down through guides 22 secured to or mounted within the platform, each of said guides 22 being shown as provided with an attaching flange, by which it is fastened to the platform. At its upper end, each plunger is provided with a head 24, while under said head is arranged a coiled expansion spring 25 encircling the plunger and bearing at its 90 lower end against the platform, or the top of the guide 22. The projecting upper portions of the plungers above the level of the platform are inclosed by a control box which extends from the floor upwardly a suitable 95 distance to entirely inclose and contain the plungers 21 and the heads 24 thereof. This box comprises a continuous front wall 26 and end walls 27 of the same height as the wall 26, the box as a whole being provided with 100 one or more bottom flanges 28, by means of which the box as a whole may be bolted to the platform or floor. The rear side of the box comprises an integral or fixed portion 29, and a pivoted and folding portion 30 105 which is hinged, as shown at 31, to the top of the fixed section 29 of the rear wall.

Hinged to the section 30, at the point 32, is the top 33 of the box, which top, when the box is thrown open, forms a support for the 110 pivoted section 30, the last named section being adapted to support the heel of the

operator as he presses the ball or toe portion of his foot upon one or the other of the heads 24. When the lamp turning mechanism is not in use at one end of the car, the 5 box is completely closed by means of the pivoted sections 30 and 33, and this prevents persons standing on the rear platform from pressing upon the plungers and operating the lamp turning mechanism at that end of 10 the car.

What is claimed is:

In a headlight for street cars, a lamp, a vertical lamp supporting shaft journaled to turn in a bearing on the car, a rock shaft 15 geared to the lamp shaft and extending rearwardly therefrom, a cross head fast on said rock shaft, foot actuated plungers opera-

tively connected with the opposite extremities of said cross head, and a combined control box and heel rest comprising a stationary plunger inclosing casing, one side of which embodies a fixed lower section and a movable upper section hinged to the lower section, and a cover hinged to said hinged section, whereby the cover is adapted to 20 form a support for said hinged section, and the latter is adapted to form a heel rest. 25

In testimony whereof I affix my signature in presence of two witnesses.

JOHN FLECK.
